UNITED STATES PATENT OFFICE.

JOHN E. GOODWILLIE, OF BROOKLYN, NEW YORK, ASSIGNOR TO INGERSOLL-RAND COMPANY, OF JERSEY CITY, NEW JERSEY, A CORPORATION OF NEW JERSEY.

SURFACE CONDENSER.

Application filed December 1, 1925. Serial No. 72,543.

This invention relates to surface condensers of the type provided with water cooled condensing tubes with which steam is adapted to contact.

5 In surface condensers of this type water is forced through the tubes usually from one end of the condenser and discharged at the opposite end. The tubes, therefore, in condensing steam transfer the heat to the water 10 causing a progressive rising temperature along the length of the tubes which results in greater specific steam condensing capacity at one end of the tubes than at the other. The tubes are spaced apart at the least practical 15 distance to permit the steam to pass through to other tubes more remote from the steam inlet. It is usually more practical to space the tubes at similar intervals at both ends rather than make the shell or casing, 20 which incloses the tubes, smaller at the discharge end of the tubes than at the inlet end. Since the cooler ends of the tubes have greater condensing capacity than the warmer ends, it therefore follows in the 25 usual condenser that steam passing down about the tubes will penetrate to a greater depth at the warmer end than at the cooler end before the steam is completely condensed. In this manner the lower tubes are 30 not utilized to their full steam condensing capacity in the colder end of the condenser which results in a loss of efficiency.

It is an object of this invention to utilize 35 the full steam condensing capacity of all of the tubes and to distribute the steam through the length of the condenser in accordance with the steam condensing capacity in the various sections. This is accomplished in this embodiment of the invention by leaving 40 a space or steam lane extending downwardly along the center of the condenser and longitudinally of the condenser and by providing baffles in the steam lane which deflect steam toward the cooler end of the condenser.

Other objects and advantages will be in part obvious and in part pointed out hereinafter.

In the drawing forming part of the specification and in which similar reference characters refer to similar parts,

Figure 1 is a longitudinal vertical section of the condenser constructed in accordance

with the practice of the invention, taken along the line 1-1 looking in the direction 55 of the arrows, and

Figure 2 is a vertical cross section taken along the line 2-2 looking in the direction of the arrows.

Referring to the drawing the condenser 60 comprises a shell or casing A having a steam inlet B and an outlet C through which condensate and uncondensable gases are withdrawn by a suitable vacuum pump (not shown). A plurality of tubes D are adapted 65 to conduct the water supplied from the supply head E suitably attached to the casing A at one end to a discharge head F at the opposite end of the casing A. The tubes are suitably sealed in the tube sheets G to 70 prevent leakage of the cooling water into the casing A.

The cooling tubes D are adapted to condense steam introduced into the interior of the casing A through the inlet B and to this 75 end are arranged transverse to the path of the steam flow and interposed between the steam inlet B and the outlet C. Near the middle of the casing A the tubes D are spaced apart to form a steam lane H 80 into which steam is adapted to flow to reach the lower banks of tubes D. The tubes D at either side of the steam lane may be placed very closely together, more so than when steam is adapted to permeate among 85 the tubes to reach the lower banks. Steam is adapted to enter the steam lane H and to spread laterally into the nest of tubes D to be condensed thereby. The steam lane H preferably extends the entire length of the 90 tubes D and is arranged to connect with all of the tubes on all levels within the casing A.

The tendency of the steam is to pass directly to the outlet C. It will be noted 95 that as the water passes through the tubes D from the supply head E toward the discharge head F its temperature rises and therefore its heat absorbing capacity is lowered. The temperature of the tubes D rises 100 correspondingly and as a result the specific condensing capacity of the tubes also decreases. The tendency of the steam therefore at the warmer ends of the tubes D is to penetrate more deeply at the warmer end. 105 of the condenser than at the cooler end.

That is, if a suitable vacuum is maintained at the outlet C to draw steam to the lowermost bank of tubes D at the warmer end of the condenser, steam passing by the tubes D at the cooler end would not penetrate as deeply since it would be condensed before reaching the lowermost bank of tubes. This would result in a loss of condensing capacity in the condenser since the cooler portions of the tubes would remain unexposed to steam. In order to utilize the full steam capacity of the condenser means is provided by this invention to distribute the steam to the cooling tubes in proportion to their steam condensing capacity. To this end baffles J, K, L and O are provided which may be horizontally placed in the steam lane H and suitably supported on brackets P attached to the tube sheets G and by means of spacing bolts Q between the baffles. Each of the baffles J, K, L and O extends from the tube sheets G at the warmer end toward the cooler end of the condenser. The uppermost baffle J is shorter than the lower baffles K, L and O, the upper baffles being progressively shorter to provide less obstruction at the cooler end of the condenser to the introduction of steam at lower levels than at the warmer end. The lowest baffle O extends the full length of the tubes D and is adapted to spread the steam out laterally about the lower tubes and to prevent steam from passing through the relatively few tubes below the baffle to the steam outlet.

Thus by the above described construction are accomplished among others the objects hereinbefore referred to.

I claim:

- 40 1. A surface condenser comprising a casing, water conducting cooling tubes within said casing having greater specific steam condensing capacity toward one end of the casing than at the other, said tubes being spaced apart to provide a steam lane, and means in said steam lane to distribute the steam within the casing and to the cooling

tubes in proportion to their steam condensing capacity.

2. A surface condenser comprising a casing having a steam inlet and an outlet for condensate and uncondensable gases remote from the inlet, a plurality of water conducting cooling tubes interposed between the steam inlet and the outlet, said tubes being spaced to provide a steam lane extending from the steam inlet toward the outlet, and means in said steam lane to distribute the steam within the casing and to the cooling tubes in proportion to their steam condensing capacity. 50

3. A surface condenser comprising a casing having a steam inlet and an outlet for condensate and uncondensable gases, a plurality of water conducting cooling tubes extending across the path of steam flow and interposed between the steam inlet and outlet, said tubes having varying specific steam condensing capacities throughout their length and spaced apart to form a steam 60 lane from the steam inlet toward the outlet, and means in said lane to distribute the steam within the casing and to the cooling tubes in proportion to their specific steam condensing capacity. 65

4. A surface condenser comprising a casing having a steam inlet and an outlet for condensate and uncondensable gases, a plurality of water conducting cooling tubes extending across the path of steam flow and interposed between the steam inlet and the outlet, said tubes having specific steam condensing capacities throughout their length and spaced apart to form a steam lane from the steam inlet toward the outlet, and means 70 in said lane to distribute the steam within the casing and to the cooling tubes in proportion to their specific steam condensing capacity. 75

In testimony whereof I have signed this specification.

JOHN E. GOODWILLIE.
